UNITED STATES PATENT OFFICE.

WILLIAM E. DAILEY, OF MINNEAPOLIS, MINNESOTA.

DESIGN FOR A GAME BOARD.

Application filed June 25, 1926. Serial No. 18,186. Term of patent 14 years.

To all whom it may concern:

Be it known that I, WILLIAM E. DAILEY, a citizen of the United States, residing at Minneapolis, in the county of Hennepin and State of Minnesota, have invented a new, original, and ornamental Design for Game Boards, of which the following is a specification, reference being had to the accompanying drawings, forming part thereof.

I claim:

The ornamental design for a game board, as shown.

WILLIAM E. DAILEY.
